UNITED STATES PATENT OFFICE.

DAVID R. BROWN, OF ST. LOUIS, MISSOURI.

HARVESTER.

SPECIFICATION forming part of Letters Patent No. 276,764, dated May 1, 1883.

Application filed February 27, 1883. (No model.)

To all whom it may concern:

Be it known that I, DAVID R. BROWN, of St. Louis, State of Missouri, have made a new and useful Improvement in Harvesters, of which the following is a full, clear, and accurate description, in which—

Figure 1 is a view in perspective of the improved harvester; Fig. 2, another view in perspective of the improved harvester; Fig. 3, a vertical transverse section taken through the harvester; Fig. 4, a vertical transverse section on an enlarged scale, showing the endless chain, rake, and parts immediately therewith connected; Fig. 5, a view in perspective of one of the rake-heads; Fig. 6, a view in perspective of one of the links of the rake-chains; Figs. 7 and 8, details showing the different positions of the rake-teeth as the rake is carried around its bearings; Fig. 9, a detail, being a vertical section, showing the mechanism for discharging the bundle, the parts being as when the discharging-arm is about to lift the bundle; Fig. 10, a similar view, the discharging-arm being raised; Fig. 11, a top view of the discharging mechanism, and Fig. 12, a vertical section taken through the lower part of the bundle-carrier.

The same letters denote the same parts.

The present invention relates to the improved means for holding the bundles, and to the combination, as hereinafter specified, of the binder mechanism, the bundle-discharging mechanism, and the bundle-carrier-holding mechanism, substantially as shown; and it consists in constructing a casing over the drive-wheel, one side of which extends upward and outward from the carrier-platform to or above the top of the drive-wheel and forms the grain-binding table, and the other side of which extends down from the top of the first-mentioned side alongside of the drive-wheel and forms one side of the grain-receptacle, and the two sides constituting a substantially A-shaped casing and a shield for the drive-wheel.

A represents a harvester in which the present improvement is embodied. Saving the improved features in question, the harvester is of the usual description.

B represents the platform, upon which the grain falls in the usual manner. The grain is thence transferred to the binder, preferably by

means of the raking device C, which is not claimed, but is shown in Figs. 1, 2, 3, 4, and 5. Two chains, c^1 c^2 , respectively near the front and the rear edge of the platform B, are carried around the sprocket-wheels c^3 c^4 upon the shafts c^5 c^6 . Rake-heads c^7 c^8 , having teeth c^9 , are attached to the chains, so that the rake-heads can be oscillated upon the points of connection with the chains. To this end the links c^{10} , to which the rake-heads are attached, (one of these links is shown in Fig. 6,) are provided with projections c^{11} , to which the rake-heads are journaled. The rake-heads are also furnished with the projections c^{12} . The device C is adjusted in the machine so as to cause the teeth c^9 upon the upper part of the device to project above the platform B, and sufficiently to enable the teeth to engage with and move the grain across the platform and into the vicinity of the binder, the operation of the device being as follows: The shafts c^5 being set in motion by suitable mechanism, (not here shown,) the teeth c^9 are moved in an upright position across the platform in the direction of the arrow in Fig. 1, the platform being slotted at b to admit of the movement of the teeth. The teeth, while moving as described, are held in an upright position by reason of the projections c^{12} of the rake-heads bearing upon the supports c^{13} . These supports are arranged sufficiently beneath the platform to allow the rake-heads to pass between the supports and the platform, but so as to cause them, through the projections c^{12} , to be turned to hold the teeth upright—that is, as the rake-heads are drawn along the projections c^{12} come in contact with the supports c^{13} , and the rake-heads are thereby tilted to bring the rake-teeth into a vertical position, and to hold them thus until the supports c^{13} are passed. After passing the wheels c^3 c^4 the teeth point downward, and in this position could be carried around to the wheels c^1 c^2 . This would, however, require more space below the platform B than is practically obtainable. Owing to the rake-heads being journaled to the chains, the teeth, on coming against the bottom D, are upturned into a horizontal position, or thereabout, in which position they remain until reaching the wheels c^1 c^2 . The teeth there assume the position shown in Fig. 7. Then, as the

chains continue to move, the teeth come against the shaft c^4 . This causes the rake-head and teeth to assume the position indicated by the broken lines in Fig. 8, the projections c^9 coming against the ends c^{11} of the supports c^{10} . The rake-heads are then turned into the position first described and the operation is repeated. The grain is passed by the rake-teeth onto the incline E. Succeeding lots of grain moved by the teeth push the grain previously lodged upon the incline farther up thereon. The usual packer-arms (not here shown) of the binder F then act to deliver the grain to the binding mechanism, (also not shown in detail, as its nature is understood,) and the binder acts in the usual manner to bind the grain. The binder F, as seen in Figs. 1, 2, 3, is located between the platform B and the driving-wheel G, and in practice is about half-way up the incline E from the platform to the top h of the casing H over the wheel. The bundles of grain being bound are then discharged over the top h of the casing. This is done by means of the discharging-arm Q, Figs. 1, 3, 9, 10, and as follows: A pinion, J, engages with the gear K. (The gear K is the usual one employed in the binder of the Wood harvester.) The pinion J also engages with the pinion L (the pinion L is behind the wheel M, Fig. 9) upon the shaft l , to which is also attached the sprocket-wheel M. The chain N transmits the motion of the wheel M to the wheel O. The shaft o of the last-named wheel has a crank, P, to which, at p , the arm Q is pivoted. A link, R, journaled at r to the frame of the binder, is pivoted to the upper end of the arm Q. The motion of the wheel O then causes the arm Q to assume the various positions shown in the full and in the broken lines in Figs. 9, 10, and the various parts being properly adjusted therefore, the lower end of the arm Q, as seen in Fig. 9, is brought, as soon as the bundle is ejected from the binder by the usual discharging mechanism, into position in the rear of the bundle. The arm Q then moves into the position of Fig. 10, and in so doing lifts the bundle upward to the top h of the casing and over into the bundle-carrier S, Figs. 1, 2, 3, 12. The binder F is, as seen more distinctly in Fig. 3, upon one side of the casing H, and the bundle-carrier S is upon the other side of the casing. This arrangement is advantageous in several respects. The weight of the bundles in the carrier is balanced by the weight of the binder mechanism. The bundle-carrier is entirely separated from the binder mechanism, so that the action of the one is not dependent upon or interfered with by the action of the other. Further, ample space is provided for a holder of a capacity sufficient for carrying enough bundles to form a large portion of a shock. The carrier S is substantially composed of the side h' of the casing H and the movable part s . The part s is upheld by the arms $s' s'$, which in turn are pivoted at s^2 to the arms $s^3 s^3$, and the latter may be rig-

idly secured to the frame, or preferably pivoted to said frame at s^6 , and retained nearly vertically (while the machine is upon roads) or horizontally (while in operation) by locking pins s^7 , entering said frame and passing under or above or through said arms. When the requisite number of bundles has been deposited in the carrier the latch s^4 is loosened, whereupon the side s opens away from the side h' , as indicated by the broken lines in Fig. 3, and as shown in Fig. 2, and the bundles drop to the ground. The side s then swings upon the bearings $s^2 s^2$ back again to the side h' , ready to receive another lot of bundles. It is desirable to have the side s so connected with the arms $s^3 s^3$ as to be self-closing. As this requires a certain amount of momentum, and as the carrier may occasionally open but slightly, I arrange to open the side s to any desirable extent, as follows: A cord, T, extends from the vicinity of the driver's seat U, over a bearing, t, to the side s at t' , and by drawing the cord T the side s can be swung open to the proper point. The side s , in opening, rises, as indicated by the broken lines in Fig. 3. The latch s^4 is operated by the cord s^5 under the control of the driver. The inner side, h^2 , of the casing H is substantially an extension of the incline E.

I make my carrier or receptacle with its transverse section in the shape of a V, or with the two sides inclining toward each other and meeting at the bottom. The effect of this construction is that when the side s is swung open the bundles will be readily and easily discharged, and will fall in a compact heap without scattering. The grain-binding table and inclined decking h^2 forms, with the inclined side h' of the grain-receptacle, a substantially A-shaped casing, under which the drive-wheel is located, and is thereby protected.

I claim—

1. In a self-binding harvester having binding mechanism between the end of the grain-platform and the drive-wheel, and means for discharging the bound bundles over the drive-wheel into a receptacle on the opposite side of the wheel, a substantially A-shaped casing, one side of which forms the grain-binding table or decking, and the other side (on the opposite side of the drive-wheel) forms one side of the receptacle for the bundles, substantially as described.
2. In a self-binding harvester having binding mechanism between the end of the grain-platform and the drive-wheel, and means for discharging the bound bundles over the drive-wheel into a receptacle on the opposite side of the wheel, a substantially A-shaped casing, one side of which forms the grain-binding table or decking, and the other side (on the opposite side of the drive-wheel) forms one side of a two-sided receptacle for the bundles, and the whole a shield or casing for the drive-wheel, substantially as described.
3. In a self-binding harvester having bind-

ing mechanism between the end of the grain-platform and the drive-wheel, and means for discharging the bound bundles over it into a receptacle on the other side, a substantially ⁴⁵ A-shaped casing above the drive-wheel, the side h' of said casing forming one side of the grain-receptacle, in combination with a movable side, s , and a latch, s' , pivoted on the casing or frame, substantially as shown and described.

4. The combination, with the shield or casing for the drive-wheel, of the supporting-arms s^3 , connected with the frame, and having pivoted at or near their free ends the short arms $s' s'$, ⁵⁰ the latter having rigidly secured thereto one side of the bundle-receptacle, substantially as described.

5. The combination, with the drive-wheel shield or casing, of the supporting-arms s^3 , having pivoted at or near their ends the short arms s' , the latter having secured thereto at an angle to their plane the board or slatted gate s , so that when said arms lie in their horizontal or normal position said board or gate will form ⁵⁵ one side of a closed bundle-carrying receptacle, substantially as described.

6. In a self-binding harvester, the combination of a binding mechanism between the end of the grain-platform and the drive-wheel, a substantially ⁶⁰ A-shaped casing, one side of which forms the grain-binding table and the other side forms one side of the bundle-receptacle, means for automatically elevating and delivering the bound bundles separately over said frame into the receptacle, and means under the control of the driver to discharge them, substantially as described.

7. In a self-binding harvester, the combination of a binding mechanism between the end ⁶⁵ of the grain-platform and the drive-wheel, a substantially A-shaped casing, one side of which forms the grain-binding table and the other side forms one side of the bundle-receptacle, the arms s^3 , the short arms s' , the suspended gate s , and cord T , secured to the top of the gate and extending within reach of the driver, substantially as and for the purpose set forth.

8. In a self-binding harvester, the combination of a binding mechanism between the end of the grain-platform and the drive-wheel, an ⁷⁰ inclined table or casing extending from said binder upward, outward, and over the drive-wheel, and an inclined table or casing extending down from the top of first casing to the bottom of the grain-receiver and forming one side thereof, with means for elevating and delivering the bound bundles separately into the receiver, substantially as described.

9. In a self-binding harvester, the combination of a binding mechanism between the end ⁷⁵ of the grain-platform and the drive-wheel, a substantially A-shaped casing, one side of which forms one side of the bundle-receptacle, arms s^3 , pivoted to said frame, and a gate, s , suspended from its upper portion to short arms ⁸⁰ on the outer ends of the arms s^3 , whereby said arms and gate can be folded together upward and against the outer side of the casing, substantially as described.

10. In a self-binding harvester, the combination, with the carrier-platform and a binding mechanism between the inner end of the carrier-platform and the drive-wheel, of a substantially ⁸⁵ A-shaped casing over the drive-wheel, one side of which forms the binding-table, and the other side of which extends down on the side of the drive-wheel, to form a chute for the discharge of the bundles and the protection of the drive-wheel, substantially as set forth.

DAVID R. BROWN.
